COMBINED TRAILER AND HEAVY DUTY WIRE STRINGER

Gerald A. M. Petersen, Santa Clara, Calif.

Application January 17, 1958, Serial No. 49,281

Term of patent 14 years

(Cl. D14—3)

Des. 184,958

PAGE 2

Fig. 1 is a perspective view of a combined trailer and heavy duty wire stringer, showing my new design therefor.

Fig. 2 is a plan view of the same.

Fig. 3 is a front elevational view of the same.

Fig. 4 is a rear elevational view of the same.

I claim:

The ornamental design for a combined trailer and heavy duty wire stringer, as shown.
